UNITED STATES PATENT OFFICE.

ALEXANDER KERR, OF LA CROSSE, WISCONSIN, ASSIGNOR OF ONE-HALF TO A. RIM, JR.,
OF LA CROSSE, WISCONSIN.

COMBINED PARKING LIGHT AND TRAFFIC SIGNAL.

Application filed October 3, 1923. Serial No. 666,327.

To all whom it may concern:

Be it known that I, ALEXANDER KERR, a citizen of the United States, residing at La Crosse, in the county of La Crosse and State of Wisconsin, have invented certain new and useful Improvements in Combined Parking Lights and Traffic Signals, of which the following is a specification.

This invention relates to a combined traffic signal and parking light for motor vehicles and seeks, among other objects, to provide a device of this character wherein, when a vehicle is being slowed down or stopped, a signal lamp will be projected for warning approaching traffic.

The invention seeks, as a further object, to provide a device of this character wherein the signal lamp will be carried by an extensible arm operable by one of the foot pedals of the vehicle so that as the vehicle is slowed down or stopped, the lamp will be coincidently moved by projection of the arm and the signal displayed thus brought to the notice of approaching traffic.

The invention seeks, as a further object, to provide a device wherein, when the signal arm is extended, a circuit will be automatically closed through the signal lamp while, when the arm is collapsed, the circuit through said lamp will be broken.

Another object, in this connection, is to provide a device wherein, when so desired, a circuit may be closed through the signal lamp when the signal arm is collapsed, so that the signal lamp may be used as a parking light.

And the invention seeks, as a still further object, to provide a device which will be neat and attractive in appearance and which may be readily applied to all conventional makes of motor vehicles.

Other and incidental objects will appear hereinafter.

In the drawings:

Figure 1 is a vertical sectional view through my improved device showing the signal arm thereof collapsed,

Figure 2 is a view similar to Figure 1, showing the signal arm extended,

Figure 3 is a sectional view on the line 3-3 of Figure 1, looking in the direction of the arrows,

Figure 4 is a sectional view on the line 4-4 of Figure 3, looking in the direction of the arrows;

Figure 5 is a sectional view on the line 5-5 of Figure 2, looking in the direction of the arrows,

Figure 6 is a detail perspective view of one of the sections of the casing of the device,

Figure 7 is a detail sectional view on the line 7-7 of Figure 4, looking in the direction of the arrows, and

Figure 8 is a detail perspective view showing the top sleeve and lever of the signal arm.

In carrying the invention into effect, I employ a flat oval-shaped casing split medially to form companion sections 10 and 11 70 provided at their lower ends with mating ears 12 through which extends a cap bolt 13 while cap screws 14 are employed at the upper ends of the sections to cooperate with the bolt 13 for detachably securing the sections together. In conjunction with the casing, I employ a base plate 15 provided at one end with a lateral lug 16 and fixed at its outer end to said lug is a guide sleeve 17 in which is journaled a pulley 18. 80

Upstanding from the base plate are companion angle plates 19 secured to the base plate by bolts 20 mounting said angle plates to receive the ears 12 of the casing therebetween, and extending through the angle plates between said ears is a bolt 21 pivotally supporting the casing, the ears being recessed at their confronting sides to accommodate the latter bolt. The device may be mounted at any suitable point upon a 90

motor vehicle and in Figure 3 of the drawings I have shown the device attached to a rear fender conventionally illustrated at 22. As will be observed, the fender is apertured to receive the guide sleeve 17 therethrough 95 so that the base plate 15 lies flat against the fender while the bolts 20 are employed to extend through the fender for connecting the base plate thereto. Thus, the device may be readily applied.

Extending vertically within the casing near the rear edge thereof is a rod 23 seated at its ends in mating recesses in the abutting edges of the sections and extending through the upper end of the rod between the sections is a pin 24 locking the rod in position. Fixed to the lower end of the rod is a split sleeve 25 secured to the rod by a pin 26 and having spaced ears 27. Slidable upon the rod is an elongated split sleeve 28 having 110

spaced ears 29 and pivotally secured between the ears 27 and 29 of the sleeves is an extensible signal arm 30 of lazy tongue structure. At the forward edge of the casing, 5 the sections thereof are cut away to define a slot 31 to freely receive the signal arm there-through and surrounding the rod 23 to bear between the sleeves 25 and 28 is a spring 32 urging the sleeve 28 upwardly upon the rod 10 for collapsing the arm within the casing.

Connected to the arm at its outer end is a cylindrical lamp casing 33 provided at one side with a lug 34 received between the adjacent ends of the outermost links of the arm 15 30 and extending through said links and through the lug is a rivet or other suitable fastening device 35 pivotally connecting the casing with the arm. Pivoted upon the lowermost of said links is a rocker arm 36 20 connected at one end with the uppermost of said links by a link 37. Projecting from the lower side of the lamp casing is a lug 38 and extending between said lug and the opposite end of said arm is a link 39. Thus, as 25 will be seen, as the signal arm 30 is extended or collapsed the lamp casing 33 will be rocked upon the arm to maintain said casing at substantially a constant level and, as best brought out in Figure 1, the casing is indented 30 at its forward edge to form a concave seat 40 for the casing when the signal arm is collapsed. Removably fitting in the casing 33 at its ends are rings 41 secured by cap screws 42 and mounted on said rings are 35 transparent closures 43 for the ends of the casing, one of said closures being frosted to show a white light toward the front of the vehicle and the other being tinted to show a red light toward the rear of the vehicle. 40 Mounted in the casing is a semi-circular socket 44 supported by a block 45 of suitable insulating material and formed on the casing beneath said socket is a sleeve 46 slidably mounting a spring pressed plunger 47 to engage the base of a lamp 48 accommodated in the socket, the plunger forming an electrical ground for the lamp.

Pivotally connected with the sleeve 28 is a lever 49 embodying a yoke 50 which is 50 formed to straddle the ears 29 of said sleeve and extending through the ends of the yoke and said ears is a pin 51 pivotally mounting the lever, it being observed that the lever is offset to clear the spring 32 upon the rod 55 23. The yoke is thus mounted to cooperate with the adjacent innermost link of the arm 30 and formed in the lower end of the yoke to slidably accommodate the rear edge of said link is a notch 52 while a short tie strap 53 is employed to extend between said link and the yoke for holding the yoke in engagement with the link. Connected to the lever at its rear end is a cord or cable 54 which is arranged to extend over the pulley 60 18 through the guide sleeve 17 and threaded

through the section 10 of the casing at its lower end to extend between the casing and said pulley is a guide tube 55 for the cable. At its forward end, the cable is connected with one of the operating pedals of the vehicle as, for instance, the brake pedal, conventionally illustrated in Figure 3 at 56.

Detachably mounted upon the side wall of the section 11 of the casing is a pair of insulating blocks 57 and clamped between said pair of blocks is a plurality of spring contacts 58, 59 and 60, notched at opposite sides thereof, as shown in detail in Figure 7, to seat in suitable slots in the blocks. The contact 59 normally engages at its upper end with the upper end of the contact 60 while the contact 58 normally engages with the contact 59 and formed in the contact 59 near the upper end thereof is an offset 61. Connected to the lower ends of the contacts 58 and 60 are feed wires 62 and 63 and extending between the lower end of the contact 59 and the lamp socket 44 is a wire 64. The wires 62 and 63 lead from a battery or other suitable source of electrical energy upon the vehicle, and an appropriate switch, not shown, is interposed in the circuit of the wire 62 so that in the day time said circuit may be broken. Formed on the casing section 11 is a lug 65 accommodating a cap screw 66 and connected with the lug by said screw is a ground lead 67. Mounted upon one of the ears of the sleeve 28 for vertical movement between the contacts 59 and 60 is a post 68, said post being in the nature of a sleeve of suitable insulating material, and extending through said sleeve is a cap screw 69 threaded into said ear for rigidly mounting the sleeve.

As will now be seen in view of the preceding description, when the pedal 56 is rocked forwardly for slowing down or stopping the vehicle, the lever 49 will, as shown in Figure 2, be rocked so that the yoke 50 of said lever will be caused to bear against the adjacent innermost link of the arm 30 while a downward pull will coincidently be communicated to the sleeve 28 for shifting said sleeve downwardly upon the rod 23 and projecting the signal arm from the casing. As brought out in Figure 4, the post 68 will normally stand between the contacts 59 and 60 so that when the signal arm is collapsed, the circuit through the lamp 48 will be broken. However, when the sleeve 28 is shifted downwardly for projecting the signal arm, as just described, the post will be moved downwardly from between the upper ends of said contacts so that, coincident with the projection of the arm, the contacts 59 and 60 will move into engagement with each other for closing the circuit through the signal lamp. Upon the release of the pedal 56, the spring 32 will, of course, immediately function to collapse

the signal arm and retract the signal lamp and, as the post 68 returns upwardly between the contacts 59 and 60, said post will engage the offset 61 of the contact 59 for separating the contacts and breaking the circuit through the signal lamp. Since the signal lamp will thus be normally extinguished, I provide the spring contact 58 in conjunction with the contact 59 in order that, at night, the signal lamp may be used as a parking light. To thus use the signal lamp, the switch in the circuit of the wire 62 is closed when current will flow through said wire and through the contact 58 to the contact 59 and thence through the wire 64 to the lamp, the contact 58 being at all times engaged with the contact 59 so that the signal lamp will remain energized regardless of the movement of the post 68.

Having thus described the invention, what is claimed as new is:

1. A traffic signal including a casing having a seat, a signal arm mounted in the casing and extensible to project therefrom, a lamp housing carried by said arm, means for extending the arm, and means for collapsing the arm within the casing and shifting said lamp housing to rest in said seat exposed at the exterior of the casing.

2. A traffic signal including a casing having a slot therein and formed at said slot with an indentation providing a seat, a signal arm mounted in the casing and extensible to project through said slot, a lamp housing carried by the arm, means for extending the arm, and means for collapsing the arm to lie entirely within the casing supporting the lamp housing to rest in said seat exposed exteriorly of the casing.

3. A traffic signal including a casing, a signal arm mounted therein and extensible to project from the casing, said arm being formed of a plurality of crossed pivotally connected links, a lamp housing pivotally connected to the outermost links of said arm, a rocker arm mounted upon one of said outermost links, a link connecting one end of said rocker arm with the lamp housing, and a link connecting the opposite end of said rocker arm with the other of said outermost links of the signal arm whereby when the signal arm is extended said rocker arm will be swung for maintaining the lamp housing at a substantially constant position with respect to the pivotal center thereof.

4. A traffic signal including a casing, an extensible signal arm mounted therein and formed of a plurality of crossed pivotally connected links, means fixedly supporting one of the links at the inner end of the arm, means movably supporting the other of the links at the inner end of the arm, and means

pivoted upon said second mentioned means and movable to coact with the latter link 65 for extending the arm.

5. A traffic signal including a casing, an extensible signal arm mounted therein and formed of a plurality of crossed pivotally connected links, means fixedly supporting 70 one of the links at the inner end of the arm, means movably supporting the other of the links at the inner end of the arm, and a lever pivoted upon said second mentioned means and movable to coact with the latter 75 link for extending the arm.

6. A traffic signal including a casing, an extensible signal arm mounted therein and formed of a plurality of crossed pivotally connected links, means fixedly supporting 80 one of the links at the inner end of the arm, reciprocable means movably supporting the other of the links at the inner end of the arm, and means pivotally mounted upon 85 said second mentioned means to coact with the latter link at the inner end of the arm for extending the arm.

7. A traffic signal including a casing, an extensible signal arm mounted therein and formed of a plurality of crossed pivotally 90 connected links, means fixedly supporting one of the links at the inner end of the arm, reciprocable means movably supporting the other of the links at the inner end of the arm, and a lever pivotally mounted upon 95 said second mentioned means to coact with the latter link at the inner end of the arm for extending the arm.

8. A traffic signal including a casing, a rod mounted therein, a sleeve fixed upon the rod, a sleeve slidable upon the rod, a signal arm formed of a plurality of crossed pivotally connected links having one of the links at the inner end thereof connected to said first mentioned sleeve and the other of the links at the inner end thereof connected to said second mentioned sleeve, a spring bearing between said sleeves tending to separate the sleeves for retracting the arm, and a lever embodying a yoke pivoted upon said second 105 mentioned sleeve to bear against the rear edge of the latter link at the inner end of the arm for swinging such link to extend the arm while shifting the movable sleeve toward the fixed sleeve.

9. A traffic signal including a casing provided with an opening and formed of mating sections having abutting edges, means securing said sections together, a rod accommodated between the sections at the abutting 110 edges thereof, a signal arm supported on said rod and extensible to project through said opening, and means for extending said arm.

In testimony whereof I affix my signature.
ALEXANDER KERR. [L. s.]
